Primary Examiner — Deanna Fluegeman

(74) *Attorney, Agent, or Firm* — Rader, Fishman & Grauer PLLC

(57) **CLAIM**

The ornamental design for a computer, as shown and described.

DESCRIPTION

FIG. 1 is a perspective view of a first embodiment of a computer showing our new design;

FIG. 2 is a front elevational view thereof;

FIG. 3 is a left side elevational view thereof;

FIG. 4 is a right side elevational view thereof; and

FIG. 5 is a top plan view thereof.

FIG. 6 is a perspective view of a second embodiment of a computer showing our new design;

FIG. 7 is a front elevational view thereof;

FIG. 8 is a left side elevational view thereof;

FIG. 9 is a right side elevational view thereof; and

FIG. 10 is a top plan view thereof.

FIG. 11 is a perspective view of a third embodiment of a computer showing our new design;

FIG. 12 is a front elevational view thereof;

FIG. 13 is a left side elevational view thereof;

FIG. 14 is a right side elevational view thereof; and,

FIG. 15 is a top plan view thereof.

The evenly-spaced broken lines illustrate unclaimed portions of the design and form no part of the claimed design. The dot-dash broken lines define boundaries of, and are not included in, the claimed design.
